UNITED STATES PATENT OFFICE.

HERBERT S. JANDUS AND NORMAN VAN HUSEN, OF DETROIT, MICHIGAN, ASSIGNEES
TO THE C. G. SPRING & BUMPER COMPANY, OF DETROIT, MICHIGAN, A CORPORA-
TION OF DELAWARE.

DESIGN FOR A CLAMP PLATE.

Original No. 76,801, dated November 6, 1928, Serial No. 24,617, filed December 23, 1927, for 3½ years.
Application for reissue filed December 20, 1928, Serial No. 29,343. Term of patent 14 years.

To all whom it may concern:

Be it known that we, HERBERT S. JANDUS and NORMAN VAN HUSEN, citizens of the United States, residing at Detroit, in the county of Wayne and State of Michigan, have invented a new, original, and ornamental Design for a Clamp Plate, of which the following is a specification, reference being had to the accompanying drawing, forming part hereof, wherein—

Fig. 1 represents a plan view and Fig. 2

represents a front elevation of a clamp plate exhibiting our new design, a bolt head being shown in dotted lines.

We claim:—

The ornamental design for a clamp plate substantially as shown and described.

In testimony whereof we hereunto affix our signatures.

HERBERT S. JANDUS.
NORMAN VAN HUSEN.
